(57) **CLAIM**

The ornamental design for a literature holder, as shown and described.

DESCRIPTION

FIG. 1 is a front elevational view of the literature holder showing the new design;

FIG. 2 is a right side elevational view of the literature holder shown in FIG. 1; the left side elevational view is a mirror image of the right side elevational view;

FIG. 3 is a rear elevational view of the literature holder shown in FIG. 1;

FIG. 4 is a top plan view of the literature holder shown in FIG. 1;

FIG. 5 is a bottom plan view of the literature holder shown in FIG. 1;

FIG. 6 is a front perspective view of the literature holder shown in FIG. 1; and,

FIG. 7 is a rear perspective view of the literature holder shown in FIG. 1.
